DRAWING OUTFIT

Frank Adler, Brooklyn, N. Y.

Application March 3, 1934, Serial No. 713,831

5 Claims. (Cl. 33—23)

The present invention relates to drawing apparatus and particularly to an outfit, adapted for use by children and art students, including, in a box or container, the necessary pencils, paints, crayons, brushes, paper, eraser, pencil sharpener and pantograph for use in reproducing a drawing, picture or the like to an enlarged scale.

While many kits or outfits have, in the past, been marketed for the use of children and art students, and while they were complete as far as they went, a very important adjunct was invariably omitted. None of these outfits provided means whereby enlargements of a photograph or a drawn subject could be made.

The present invention, therefore, contemplates the provision of a drawing outfit which includes simple and inexpensive pantograph means for making enlargements.

Another important feature of the invention resides in the provision of a pantograph of the simple elastic element type which may be proportioned so enlargement of various degrees may be easily and quickly drawn.

A further object of the invention is the provision in an elastic element pantograph of slide means to change the length of one leg of the pantograph in relation to the other and thereby being enabled to attain enlargements of varying sizes.

Other features and objects of the invention lie in the particular improved construction of the pantograph; in the improved pantograph slide; in the means on the non-adjustable leg of the pantograph element for supporting the scribe or pencil intermediate its length; etc.

These advantageous features are accomplished by the novel and practical construction, combination and arrangement of parts hereinafter disclosed and illustrated in the accompanying drawing, constituting an essential part of the disclosure, and in which:

Fig. 1 is a perspective view of a kit or outfit, open and ready for use incorporating features of the invention.

Fig. 2 is a plan view partly broken and to an enlarged scale of the pantograph features of the invention.

Fig. 3 is an end detail section of the pantograph slide.

Fig. 4 is a side view thereof.

Referring to the drawing in greater detail the outfit is shown as being carried in a box or case comprising the portions 5 and 6 hinged at 7. The portion 5 is preferably provided with means

such as the feet 8 to provide a tilt to the paper 9 upon which the drawings are to be made. So as to retain the cover portion 6 of the case in a substantially upright position means such as the braces 10 may be utilized.

Each portion 5 and 6 of the case may serve to carry and support various items. In this instance it is preferred that the cover 6 carry a pencil box 11 and be provided with racks 12 and 13 for the respective original drawings or photos 14 and the copied enlargements 15.

The portion 5 of the case is preferably fitted as shown with a tray 16 for colored pencils, a tray 17 for crayons, a box of paints 18 also housing brushes, a water dish 19, an eraser tray 20, a pencil sharpener tray 21 and such divers other trays, recesses, compartments, etc., as may be deemed necessary to complete the utility of the outfit.

These trays, compartments, etc., are suitably arranged in the case to provide room in the center of one end thereof for a pantograph 22. This pantograph is preferably of the type which employs an elastic member such as the coiled spring 23 anchored at one end as at 24.

Midway of its length the member 23 is provided with a tracing point 25 and at its free end with means such as the socket 26 receptive of a scribe, pencil, or the like 27.

That leg of the member 23 between the tracing point and the socket 26 may be provided with one or more sockets 28, 29 thereby affording means whereby enlargements of lesser size than one made with the scribe or pencil in the socket 26 may be made.

In practise it is preferred that the leg between 24 and 25 and the leg between 25 and 26 be substantially equal. This provides for a two to one enlargement of a subject such as at 30 drawn on the sheet represented at 9a.

In order to obtain greater enlargements of the subject 30 it is necessary to shorten the effective length of the leg 24—25. This may be accomplished in several ways, one being to provide a slide 31 movable along a rail 32 so that it may overlie any desired point of this leg of the member 23.

The slide is preferably formed as a saddle 33, the lower ends of whose legs serve to retain a spring 34 adapted to impinge against the lower face of the rail and which is provided with a member 35 adapted to bear against the member 23. A knob 36 is provided for manipulation and a pointer 37 is employed to be read in connection with the graduations 38.

In the drawing (Fig. 2) the pantograph is shown as set to make a two to one enlargement. If it is desired to make a one-and-one-half to one enlargement, the scribe is placed in the socket 29 and this enlargement would take form on the sheet 30. With the scribe in the socket 28 an enlargement of one and a quarter to one could be made on the sheet 40.

When it is desired to make a two and a half to one, three to one, four to one or five to one enlargement, it is only necessary to raise the knob 36 and move the slide 31 so its pointer 37 aligns with the desired graduation 38. Upon release of the knob the member 23 will be pinched by the member 35 of the slide so the proper effective length of the leg 24-25 is obtained.

When out of use the scribe or pencil 27 may be inserted in a clip such as 41 for neatness and compactness.

From the foregoing it will be seen that a simple device for the purpose has been disclosed in the preferred form of its embodiment, but it is not desired to restrict the details to the exact construction shown, it being obvious that changes, not involving the exercise of invention, may be made without departing from the scope of the appended claims.

Having thus described my invention, what I claim as new and desire to secure by Letters Patent, is:

1. In a drawing outfit a pantograph comprising an elastic member anchored at one end to a support, a tracing point fixed on the elastic member intermediate the ends thereof, a pencil socket at the other end and slide clamp means associated with the elastic member and cooperating with the support to vary the effective length of the elastic member between its anchorage and the tracing point.

2. In a drawing outfit a pantograph comprising

an elastic member anchored at one end, a tracing point midway of the length of the elastic member, a pencil socket at the other end and means to shorten the effective length of the elastic member between its anchorage and the tracing point said means comprising a rail, and a slide slidably engaged with and movable along the rail and adapted to bear against a portion of the elastic member to clamp it to the rail.

3. A slide for varying the effective length of one leg of a pantograph having an elastic member and a graduated rail, comprising a saddle slidably mounted on the rail, means carried by the saddle adapted to bear against a selected portion of the elastic member, spring means to cause pressure of said saddle carried means on said elastic member and knob means to facilitate manipulation of the slide.

4. A slide for varying the effective length of one leg of a pantograph having an elastic member and a graduated rail, comprising a saddle slidably mounted on the rail, means carried by the saddle adapted to bear against a selected portion of the elastic member, spring means to cause pressure of said saddle carried means on said elastic member, knob means to facilitate manipulation of the slide, and a pointer on said slide readable in connection with the graduations on the rail.

5. In a drawing outfit a pantograph comprising an elastic member anchored at one end, a tracing point fixedly attached to the elastic member intermediate the ends thereof, a pencil socket at the other end and means to shorten the effective length of the elastic member between its anchorage and the tracing point, said means comprising a rail, and an element slidable on said rail adapted to clamp the elastic member to the rail at selected points.

FRANK ADLER.
